United States Patent Office.

JOHN R. BULLIS, OF BOWLING GREEN, OHIO.

Letters Patent No. 86,208, dated January 26, 1869.

IMPROVEMENT IN JOINTER FOR CIRCULAR SAWs.

The Schedule referred to in these Letters Patent and making part of the same.

To all whom it may concern:

Be it known that I, JOHN R. BULLIS, of Bowling Green, in the county of Wood, and State of Ohio, have invented new and useful Improvements in Circular-Saw Jointers; and I do hereby declare that the following is a full and exact description of the same, reference being had to the accompanying drawings, and to the letters of reference marked thereon.

This invention relates to a simple device for jointing circular saws, and consists mainly of a frame, holding a file, which latter is advanced, as the teeth are cut away, by means of an adjustable sash-slide.

The details of construction, and manner of operation, will be fully described hereinafter.

In the drawings—

Figure 1 represents a perspective view, and Figure 2, a sectional elevation.

In order that those skilled in the art to which my invention appertains may be enabled to make and use the same, I will now proceed to describe its construction and operation.

A represents the frame-work of the machine, consisting of the beams *a a* and uprights *a' a'*, which are suitably braced and connected by cross-beams, as shown.

B B represent inclined ways up the front, upon which sides the sash B¹, which is provided at its front end with a pivoted bar, *b*, having a socket, in which the upper end of the file is secured.

The sash is also provided with the screw-rod *b¹* and hand-nut *b²*.

B² represents a cross-beam, securely attached to the ways B, which extends across the sash B¹, and furnishes a bearing-surface for the hand-nut *b²* to press against. The sash-slide is suitably cut away in the

centre, in order to move freely without interfering with this beam.

C represents a screw-rod, provided with the pivoted brace *c*, which is arranged to press against the back of the file at any angle. This rod is screwed in cross-beams, suitably located, and is operated by means of a hand-nut, as shown.

D represents a cross-beam, in which the lower end of a file, E, is slipped. This is so arranged as to turn freely as the file changes position.

From this description the operation of my invention will be readily understood.

When it is desired to use the machine, it should be placed in front of the moving saw, with the file bearing against the largest teeth. The operator, standing behind the machine, with his feet upon the bed-pieces, to keep it steady, advances the slide and brace, as the teeth are cut away, until all are touched by the file and made uniform in height.

I do not claim broadly the manner of jointing a saw by advancing a file by means of a screw, for such an arrangement is shown in the patent of W. B. Noyes, March 3, 1868; but

What I do claim, and desire to secure by Letters Patent, is—

The arrangement of the frame A with ways B, pivoted cross-beams *b*, D, and adjustable sash B¹, with file E and brace *c*, when all the parts are constructed as described, and for the purpose set forth.

This specification signed and witnessed, this 9th day of October, 1868.

JOHN R. BULLIS.
